DESIGN FOR A CASING FOR AN ELECTRICAL WATER PURIFYING UNIT OF THE OZONE TYPE FOR USE WITH A BOTTLE TYPE WATER COOLER

James M. Daily, Chicago, Ill., assignor to American Ozone Company, Chicago, Ill., a corporation of Illinois

Application May 23, 1934, Serial No. 51,892

Term of patent 14 years

To all whom it may concern:

Be it known that I, JAMES M. DAILY, a citizen of the United States, residing at Chicago, in the county of Cook and State of Illinois, have invented a new, original, and ornamental Design for a Casing for an Electrical Water Purifying Unit of the Ozone Type for Use with a Bottle Type Water Cooler, of which the following is a specification, reference being had to the accompanying drawing, forming a part thereof.

Figure 1 of the drawing is a perspective of a casing embodying the new design; and

Figure 2 is a top view of the casing.

I claim:

The ornamental design for a casing for an electric water purifying unit of the ozone type for use with a bottle type water cooler substantially as shown.

Signed at Chicago, Illinois, this 21st day of May, 1934.

JAMES M. DAILY.
